UNITED STATES PATENT OFFICE.

WALTER P. LAFFERTY, OF PHILADELPHIA, PENNSYLVANIA.

CENTRIFUGAL MACHINE.

SPECIFICATION forming part of Letters Patent No. 695,158, dated March 11, 1902.

Application filed December 16, 1901. Serial No. 86,035. (No model.)

To all whom it may concern:

Be it known that I, WALTER P. LAFFERTY, of Philadelphia, in the State of Pennsylvania, have invented certain new and useful Improvements in Centrifugal Machines, whereof the following is a specification, reference being had to the accompanying drawings.

My invention relates to centrifugal separators of the type wherein an imperforate drum is fixed for rotation upon a vertical spindle which is supported to rotate and gyrate within an inclosing casing.

The object of my invention is to provide a machine which is adapted by its peculiar construction to rapidly and efficiently separate liquid from starch and similar substances.

My improvements comprise certain details of construction hereinafter more definitely specified and claimed.

In the accompanying drawings, Figure 1 is a central vertical section through a machine conveniently embodying my invention. Fig. 2 is a sectional view of said machine, taken on the line 2 2 of Fig. 1. Fig. 3 is a sectional view of said machine, taken on the line 3 3 of Fig. 1.

In said figures, A is the base-plate, upon which are mounted the tubular standards B, which uphold the casing C, which is maintained in fixed relation with the base-plate by means of the bolts D, extending through said standards. Said bolts are provided with heads d, socketed in the bottom of said casing C, and jam-nuts d' beneath said base-plate.

The foot-block A' is fixed upon the base-plate A in concentric relation with the casing C, and the step-bushing a' is mounted to gyrate therein and support the weight of the spindle E upon the thrust-washers a². The

drum F, which is fixed upon the top of the spindle E, comprises a bottom frame F', having a central hub f', fitted to said spindle, and medial and peripheral annular flanges f² and f³, connected by radial arms f⁴. The imperforate cylindrical shell F² of the drum is fixed at its lower edge upon the peripheral flange f³ and is supported and stiffened by the circumferential bands f⁵. The separate

annular bottom plate F³ extends from the peripheral flange f³ to the medial flange f², and the discharge-opening F⁴, comprising the radial interstices between the arms f⁴, extend-

ing from the hub f' to the flange f², is provided with the removable cover G, seated upon the hub f', overlapping the edge of the bottom plate F³.

The annular top plate F⁵ is fixed at the upper edge of the shell F², and the radial imperforate vanes H are fitted closely to the periphery of the drum F in channels h upon the bottom plate F³ and in channels h' upon the top plate F⁵, so as to be readily removed when it is desired to empty the solid contents of the drum through the discharge-opening F⁴. Said vanes H are stiffened at their inner edges by flanges h², projecting in the direction of rotation of the drum.

The spindle E and drum F are rotated by means of the band-wheel I, which is fixed by the set-screw i upon the lower extremity of the spindle. It being found in practice that the center of gravity of the loaded drum does not always coincide with the axis of said spindle, I have provided means to support said spindle beneath said drum, arranged to permit of the gyration thereof due to any such eccentricity, and thus avoid undue strain and friction upon the bearings.

The bottom plate C² of the casing C has a vertical flange C³ formed at the margin of the discharge-opening C⁴, the latter being of somewhat greater radius than the opening F⁴ in the drum and in registry therewith. Said flange C³ is provided with a series of radial openings c³, extending to its top, arranged to receive respective seat-rings j for the springs J, which surround the rods K and abut against the washers k thereon. Each of said washers k is arranged to be longitudinally adjusted upon its respective rod K by means of the jam-nuts K', and the series of rods K are connected by the pins l with the bearing-sleeve L, which surrounds the spindle E below the drum F. The parts described are therefore so arranged as to yieldingly support said spindle and permit of its gyration, as aforesaid, although the set of the springs is such as to normally maintain said spindle and drum in concentric relation with the casing C.

The discharge-chute M is fixed by the bolts m upon the bottom plate C² of the casing C and comprises the sleeve M', in concentric relation with said casing. Said sleeve M' is

made of conical form, as shown, to permit of the gyration of said spindle with the least diameter of the lower extremity m' of the sleeve, which is entered in the oil-receptacle i' of the driving-wheel I . The lower extremity l' of the sleeve L overhangs the upper extremity m^2 of said sleeve M' , so as to exclude from said sleeve the material discharged down said chute.

10 In order that the rotation of the drum and spindle may be promptly checked when a charge of material has been treated within said drum, I provide the driving-wheel I with a brake-flange I' in fixed concentric relation therewith. Said brake-flange is encircled by a normally stationary brake-band N , whose opposite extremities $n\ n'$ are secured upon the oppositely-extending arms $o\ o'$ of the brake-lever O , which is mounted to oscillate upon 15 the standard P , fixed upon the base-plate A . The relation of the brake parts is such that when the lever O is in the position shown in Fig. 3 the driving-wheel I and the parts connected therewith are free to rotate, while the band N remains stationary. When, however, said lever is shifted in the direction of the arrow upon Fig. 3, said band N is caused to grip the flange I' , and thus check the rotation of the driving-wheel, spindle, and drum.

20 As a matter of convenience the base-plate A is provided with a standard Q , arranged to support hangers Q' for guide-pulleys Q^2 , which, as indicated, are adjusted and secured in proper relation with the band R , arranged to drive the wheel I .

30 The operation of the device is as follows: The parts being in the position shown in Fig. 1, the material to be treated is delivered within the drum F through the central opening in 40 the cover C' of the casing C and the top plate F^5 of the drum. The drum being thereupon rotated at the proper speed gyrates in accordance with the location of its center of gravity from instant to instant, the tensile strain upon 45 the rods K of the springs J tending, however, to maintain said drum in concentric relation with the casing. As the result of the centrifugal action within the rotating drum the solid portion of the material treated is shifted toward the shell F^2 , and the liquid portion thereof is discharged over the annular top F^5 beneath the cover C' and falls within the casing C . Said liquid is drained through the outlet C^5 at the bottom of the casing and is disposed of in any convenient manner. The centrifugal action within the drum is of course dependent not merely upon the speed of rotation of the drum, but upon the speed of rotation of its contents, and whereas a considerable 55 loss in efficiency results from the employment of an ordinary drum which may rotate independently of its contents it is to be noted that by my improvement the imperforate vanes H engage the material within the drum and compel its rotation with the latter without interference with the centrifugal action. When, however, it is desired to remove the concen-

trated product from the drum, the speed of rotation of the drum and spindle is checked by means of the lever O and brake-band N , 70 and the rotation of the contents of the drum being also checked by the aforesaid engagement therewith of said vanes H the cover G is uplifted from the position shown in Fig. 1. The vanes H are withdrawn bodily through 75 the top of the drum, and the concentrated product is discharged through the opening F^4 in the drum in registry with the opening C^4 in the bottom C^2 of the casing C , and, falling within the chute M , is discharged laterally 80 to be disposed of in any convenient manner.

It is to be noted that by reason of the peculiar construction of the mechanism above described all of the parts are readily accessible for cleaning, adjustment, repairs, &c. 85 The cover C' of the casing C being removed and the set-screw i retracted, the drum F and spindle E may be uplifted and removed from the casing. Access is thus had to all of the springs J and the rods K connected therewith, 90 which may be independently adjusted in position or be bodily raised and removed, together with the sleeve L , the openings c^3 , extending to the top of the flange C^3 , permitting such a manipulation of the parts. The chute 95 M may of course be removed by withdrawing the bolts m , which serve to fix it upon the bottom casing-plate C^2 .

I do not desire to limit myself to the precise arrangement of the parts which I have shown, 100 as it is obvious that various modifications may be made therein without departing from the spirit of my invention.

I claim—

1. In a centrifugal machine, the combination with a stationary casing comprising a discharge-opening; of a spindle arranged to rotate and gyrate in said casing; a drum fixed on the upper end of said spindle within said casing; vanes in said drum; a discharge-opening in said drum in registry with the discharge-opening in said casing; a cover for said opening; a bearing-sleeve embracing said spindle, intermediate of said drum and casing; means connected to said bearing-sleeve arranged to 115 yieldingly support said spindle; and means to rotate said spindle and drum, substantially as set forth.

2. In a centrifugal machine, the combination with a stationary casing comprising a discharge-opening; of a spindle arranged to rotate and gyrate in said casing; a drum fixed on the upper end of said spindle within said casing; vanes in said drum; a discharge-opening in said drum in registry with the discharge-opening in said casing; a cover for said opening; a bearing-sleeve embracing said spindle, intermediate of said drum and casing; a series of tension-rods extending radially from said bearing-sleeve; springs surrounding said rods and abutting against said casing; means to adjust the stress of said springs upon said rods; and means to rotate said spindle and drum, substantially as set forth.

3. In a centrifugal machine, the combination with a stationary casing comprising a discharge-opening; of a chute secured to said casing in registry with said opening; a sleeve on said chute; a spindle arranged to rotate and gyrate in said sleeve; a drum secured on the upper end of said spindle within said casing; vanes in said drum; a discharge-opening in said drum in registry with the discharge-opening in said casing; a discharge-opening in said casing; a removable cover for said opening; means arranged to yieldingly support the upper end of said spindle; and means to rotate said spindle and drum, substantially as set forth.

4. In a centrifugal machine, the combination with a stationary casing comprising a discharge-opening; of a chute secured to said casing in registry with said opening; a conical sleeve on said chute; a spindle arranged to rotate and gyrate in said sleeve; a drum secured on the upper end of said spindle within said casing; vanes in said drum; a discharge-opening in said drum in registry with the discharge-opening in said casing; a removable cover for said opening; means arranged to yieldingly support the upper end of said spindle; and means to rotate said spindle and drum, substantially as set forth.

5. In a centrifugal machine, the combination with a stationary casing comprising a discharge-opening; of a chute secured to said casing in registry with said opening; a stationary sleeve on said chute; a spindle arranged to rotate and gyrate in said sleeve; a drum secured on the upper end of said spindle within said casing; vanes in said drum; a discharge-opening in said drum in registry with the discharge-opening in said casing; a removable cover for said opening; a bearing-sleeve embracing said spindle and overhanging the upper end of said stationary sleeve; means connected to said bearing-sleeve arranged to yieldingly support the upper end of said spindle; and means to rotate said spindle and drum, substantially as set forth.

6. In a centrifugal machine, the combination with a stationary casing comprising a dis-

charge-opening; of a chute secured to said casing in registry with said opening; a stationary sleeve on said chute; a spindle arranged to rotate and gyrate in said sleeve; a drum secured on the upper end of said spindle within said casing; vanes in said drum; a discharge-opening in said drum in registry with the discharge-opening in said casing; a removable cover for said opening; a vertically-extending flange around the margin of the opening in said casing; openings in said flange; a bearing-sleeve fixed to said spindle; rods, each connected at one end to said bearing-sleeve, and projecting through the respective openings in said flange; nuts on the outer ends of said rods; springs embracing said rods and abutting against said flange and said nuts; and means to rotate said spindle and drum, substantially as set forth.

7. In a centrifugal machine, the combination with a stationary inclosing casing; of a rotary spindle in said casing; an imperforate drum within said casing, fixed upon the top of said spindle; a step bearing in said casing supporting the lower extremity of said spindle; a bearing-sleeve surrounding the upper portion of said spindle, beneath said drum; means to yieldingly support said bearing-sleeve with respect to said casing; radial openings in the bottom of said drum, concentric with said spindle; a removable cover for said openings; a vertically-dependant flange on said drum, at the margin of said openings; an opening in the bottom of said casing concentric with said spindle, of greater radius than the openings in said drum; a vertically-extending flange on said casing at the margin of said opening; and a discharge-chute, fixed with respect to said casing, in registry with said openings, substantially as set forth.

Signed as Philadelphia, Pennsylvania, this 14th day of December, 1901.
